JEWELRY DISPLAY BOX

Bryan F. Commans, Overland Park, Kans., and Irene Irvin, Kansas City, Mo., assignors to The House of Commons, Inc., Kansas City, Mo.

Filed Oct. 12, 1970, Ser. No. 25,448

Term of patent 3½ years

Int. Cl. D9—03

U.S. Cl. D9—239

Fig. 1.

Fig. 4.

Fig. 2.

Fig. 5.

Fig. 3.

FIG. 1 is a front elevational view of a jewelry display box;

FIG. 2 is a top plan view;

FIG. 3 is a bottom view;

FIG. 4 is an elevational view showing one side; and

FIG. 5 is a rear elevational view.

That side of the article opposite to the side illustrated in FIG. 4 has the same appearance and ornamentation as depicted in FIG. 4.

We claim:

The ornamental design for a jewelry display box, as shown and described.
